US0D1073674S

(12) **United States Design Patent** (10) **Patent No.:** **US D1,073,674 S**
(45) **Date of Patent:** **** May 6, 2025**

(54) **COMPUTER MONITOR**

(71) Applicant: **LG DISPLAY CO., LTD.**, Seoul (KR)

(72) Inventors: **Yeongho Kim**, Paju-si (KR); **Wonjae Hwang**, Paju-si (KR)

(73) Assignee: **LG DISPLAY CO., LTD.**, Seoul (KR)

(**) Term: **15 Years**

(21) Appl. No.: **29/884,373**

(22) Filed: **Feb. 10, 2023**

(30) **Foreign Application Priority Data**

Sep. 2, 2022 (KR) 30-2022-0035914

(57) **CLAIM**

The ornamental design for a computer monitor as shown and described.

DESCRIPTION

FIG. 1 is a front, right, top perspective view of a computer monitor showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is an enlarged view of portion "9" of FIG. 2;

FIG. 10 is an enlarged view of portion "10" of FIG. 4;

FIG. 11 is an enlarged view of portion "11" of FIG. 4;

FIG. 12 is an enlarged view of portion "12" of FIG. 6; and,

FIG. 13 is an enlarged view of portion "13" of FIG. 7.

The even dash broken lines depict portions of the computer monitor that form no part of the claimed design. The dash-dot-dot broken lines represent the extents of the enlarged detail views and form no part of the claim.

1 Claim, 13 Drawing Sheets
